UNITED STATES PATENT OFFICE.

ALBERT F. WARD, OF SAN FRANCISCO, CALIFORNIA.

ADVERTISING DEVICE.

1,290,688.

Specification of Letters Patent.

Patented Jan. 7, 1919.

Application filed January 31, 1918. Serial No. 214,719.

To all whom it may concern:

Be it known that I, ALBERT F. WARD, a citizen of the United States, residing at the city and county of San Francisco and State 5 of California, have invented new and useful Improvements in Advertising Devices, of which the following is a specification.

This invention relates to an advertising device.

10 One of the objects of the present invention is to provide a comic or other suitable form of picture to be used for amusement, advertising or other purposes, which is provided with openings for the eyes and the mouth, 15 and in conjunction therewith to provide a pair of superposed movable plates which are adapted to be positioned directly behind the picture, one of said plates having eyes formed thereon in register with the eye openings in the picture and the other plate having a lower lip positioned in register with the mouth opening in the picture. Another 20 object of the invention is to provide means for imparting movement to each plate, as will hereinafter be described, to give the picture a life-like appearance and action. Further objects will hereinafter appear.

The invention consists of the parts and the construction and combination of parts 25 as hereinafter more fully described and claimed, having reference to the accompanying drawings, in which—

Figure 1 is a front view of the picture, showing the application of the invention.

30 Fig. 2 is a front view of the central plate which carries the operating mechanism.

Fig. 3 is a vertical cross section on line 3—3 of Fig. 1.

Referring to the drawings in detail, A indicates a plate constructed of tin, or any other suitable material, on which is painted, or otherwise formed, a picture, such as shown at 2. The plate is cut out to conform to the outline of the picture, and the edge thus 40 formed is preferably inturned, as shown at 3, to permit it to be attached to a rear plate 2^a, upon which is painted another picture or a picture similar to the one shown on the front plate 2.

45 Formed in each of the plates 2 and 2^a is a pair of openings 4 for the eyes and an open-

ing 5 for the mouth. Interposed between the plates 2 and 2^a, which are maintained in spaced relation to each other as shown in Fig. 3, is a frame plate 6. This plate is 55 suitably secured between the picture plates and is provided for the purpose of supporting an operating mechanism, hereinafter to be described. The frame plate may be rectangular in shape, or may conform to the 60 outline of the picture plates, as shown in Fig. 2. The upper portion is cut out, as shown at 7, to receive a U-shaped sliding frame 8 consisting of a bent section of wire. One leg of the wire 9 is carried in a vertical 65 bearing 10 and its upper end is hook-shaped, as at 11, to project through the forked end 12 of a bell-crank 13 which is pivotally secured to the frame plate, as at 14. The lower end of the bell-crank is provided with 70 a weight 15 and has such functions as a pendulum.

Straddling the wire frame 8 is a plate 16 which is U-shaped in cross section. This plate is slidably mounted on the wire frame 75 8 and it has painted on each side eyes 17 which register with the eye openings in the picture plates. Movement of the pendulum 15 about its pivot 14 is transmitted through the fork-shaped end of the bell-crank to 80 raise and lower the wire frame and the plate 16 carried thereby. The eyes painted on the plate will, therefore, move up and down with relation to the eye openings 4 in the pictures and will give a life-like impression. The 85 plate also has a tendency to slide horizontally on the wire frame 8 from the full line position shown in Fig. 2 to the dotted line position shown at 16^a, thus permitting the eyes to move sidewise and further accentuate 90 a life-like action.

The frame plate is also cut out near the lower end, as shown at 18, to receive a plate 19 which is also U-shaped in cross section to straddle a wire frame 20. This frame is 95 also carried in a vertical bearing member 21 and is also actuated by a pendulum 22 similar to the one previously described. The plate 19 is cut out, as shown at 23, to expose a set of teeth 24 which are painted on the 100 frame plate. The portion of the plate just below the opening 23 has a lower lip painted

thereon so that vertical movement imparted to the plate will give the impression that the mouth is being opened and closed. The teeth 24 are thus exposed from time to time 5 as the lower lip moves and as the plate 19 may slide on the wire frame 20 horizontally in a manner similar to the upper plate 17 it is obvious that a side movement may also be imparted to the lip.

- 10 The device as a whole may be mounted on the wind-shield of an automobile where the vibrations and rocking movements of same cause the pendulums to swing and impart movement to the lip and eye plates. The 15 device may, therefore, serve as a source of amusement when thus positioned to the occupants of the automobile or it may serve as an advertising device which should attract considerable attention as the constant movements of the eyes and mouth will obviously give the picture a life-like action. The device may also be mounted in a store window or any other suitable place, it being desirable in such instances to place it on a 20 mechanically operated rocker or vibrator having sufficient movement to actuate the pendulums. The portions of the picture plates surrounding the eyes and mouth are preferably turned in, as shown at 4^a in Fig. 25 30 3, to permit the eye and mouth plates to form a close register with the openings, the purpose of such a construction being to disguise as much as possible the fact that the eyes, teeth and lips are formed on separate 35 plates.

While the plates are here shown as formed with inturned edges 3 to permit the same to be secured with relation to each other, it is obvious that a channel-shaped member or 40 any other suitable means may be employed for this purpose. I also wish it understood that the materials and finish of the several parts of the device may be such as the experience and judgment of the manufacturer 45 may dictate.

Having thus described my invention, what I claim and desire to secure by Letters Patent is—

1. In a device of the character described, 50 a plate having a face formed thereon, said plate having openings formed therein in register with the eyes and mouth, a plate mounted behind the face plate having eyes formed thereon, a second plate mounted behind the face plate having a lip formed thereon, and means connected with each of said plates adapted to move said plates independently of each other.

2. In a device of the character described, 60 a plate having a face formed thereon, said plate having a pair of eye openings and a mouth opening formed therein, a stationary frame plate positioned behind the face plate, a plate carried by the frame having eyes 65 formed thereon in register with the eye

openings in the face plate, a second plate having a lip formed thereon in register with the mouth opening of the face plate, also mounted on the frame, a weighted lever connected with the eye plate adapted to move 70 the same when the frame and face plate are tilted, and a weight actuated mechanism similarly connected with the lip plate.

3. In a device of the character described, 75 a pair of interspaced plates having pictures formed on their exterior surfaces, said plates having a pair of eye openings and a mouth opening formed therein, a stationary frame plate positioned between the picture plates, a plate carried by the frame plate having 80 eyes formed thereon in register with the eye openings in the picture plates, a second plate having a lip formed thereon in register with the mouth opening in the picture plates, and means for imparting movement 85 to each plate.

4. In a device of the character described, a pair of interspaced plates having pictures formed on their exterior surfaces, said plates having a pair of eye openings and a mouth 90 opening formed therein, a stationary frame plate positioned between the picture plates, a plate carried by the frame plate having eyes formed thereon in register with the eye 95 openings in the picture plates, a second plate having a lip formed thereon in register with the mouth opening in the picture plates, and a pendulum mechanism adapted to impart movement to each plate.

5. In a device of the character described, a 100 pair of interspaced plates having pictures formed on their exterior surfaces, said plates having a pair of eye openings and a mouth opening formed therein, a stationary frame plate positioned between the picture plates, a plate carried by the frame plate having eyes formed thereon in register with the eye 105 openings in the picture plates, a second plate having a lip formed thereon in register with the mouth opening in the picture plates, a pendulum mechanism adapted to impart 110 movement to each plate, and teeth formed on the frame plate in register with the mouth openings in the picture plates.

6. In a device of the character described, 115 a pair of interspaced picture plates, each plate having a pair of eye openings and a mouth opening formed therein, a stationary frame plate positioned between the picture plates, a sliding frame having vertical 120 movement, a pendulum adapted to impart vertical movement to said frame, a plate U-shaped in cross section slidably mounted on the sliding frame, said plate having eyes formed thereon adapted to register with the 125 eye openings in the picture plates, a second sliding frame having vertical movement, a pendulum mechanism adapted to impart said vertical movement, said plate being U-shaped in cross section and having a pair of 130

openings formed therein registering with the mouth openings in the picture plates, a lip painted on each side of the plate, and teeth painted on each side of the frame plate 5 in register with the mouth openings of the picture plates.

In testimony whereof I have hereunto set

my hand in the presence of two subscribing witnesses.

ALBERT F. WARD.
